Primary Examiner — Cynthia R Underwood

(74) Attorney, Agent, or Firm — Jose Cherson Weissbrot

(57) **CLAIM**

I claim the ornamental design for a cable railing kit, as shown and described.

DESCRIPTION

FIG. 1 is a Perspective view of a cable railing kit showing my new design;

FIG. 2 is a Front view thereof;

FIG. 3 is a Back view thereof;

FIG. 4 is a Right-side view thereof;

FIG. 5 is a Left-side view thereof;

FIG. 6 is a Top view thereof;

FIG. 7 is a Bottom view thereof; and,

FIG. 8 is a section view of a cable railing kit taken along line 8-8 in FIG. 5.

1 Claim, 8 Drawing Sheets
